J. P. YOUNG.
SANITARY STOOL SEAT COVER.
APPLICATION FILED JUNE 20, 1919.

1,377,541.

Patented May 10, 1921.

UNITED STATES PATENT OFFICE.

JACOB P. YOUNG, OF HUNTINGTON, INDIANA.

SANITARY STOOL-SEAT COVER.

1,377,541.

Specification of Letters Patent.

Patented May 10, 1921.

Application filed June 20, 1919. Serial No. 305,472.

To all whom it may concern:

Be it known that I, JACOB P. YOUNG, a citizen of the United States, residing at Huntington, in the county of Huntington and State of Indiana, have invented a new and useful Sanitary Stool-Seat Cover, of which the following is a specification.

This invention has reference to sanitary appliances to be used in connection with 10 closet seats and it primarily has for its purposes to provide an appliance of the general type stated in the nature of a thin sheet of paper, preferably medicated or sterilized, that includes a main portion 15 adapted to serve as a seat protector, a front portion that serves as an apron for hanging over the front edge of the seat for protecting the limbs and clothing of the user, a supplemental member fitting over the 20 usual hinged seat cover to protect the back of the user, and including a member that serves as a means for holding the back protecting portion in position when applied for use.

25 Another object of my invention is to provide a sanitary appliance, of the kind mentioned, comprising a single sheet of paper or other similar material, having different portions relatively so connected whereby the 30 sheet may be applied, not alone over the closet seat but also over the other portions of the closet bowl and the seat cover with which parts of the body contact when at stool, and in such manner that the spread 35 of venereal diseases are prevented and natural evacuation encouraged.

With the above objects in view, my invention embodies, in a sanitary appliance, in the nature of a paper sheet that includes 40 several distinct portions shaped for special purposes, hereinafter stated, and so connected that the sheet may be quickly applied and held from being easily displaced and capable of being easily and compactly so 45 folded that the sheet may be properly unfolded and ready for use, and after use as quickly removed and disposed of.

50 My invention further consists in the peculiar formation of the sanitary sheet hereinafter explained in detail, specifically stated in the appended claims, and illustrated in the accompanying drawing, in which:

Figure 1 is a perspective view of my invention, the same being shown as 55 operatively applied to a conventional water closet,

including the bowl, the seat and the hinged seat cover.

Fig. 2 is a longitudinal section taken substantially on the line 2—2 on Fig. 1, parts of the bowl being shown in side elevation. 60

Fig. 3 is a diagrammatic plan view of the appliance in the fully extended position.

Fig. 4 is a perspective view of one of the appliances or seat cover is folded up.

My improved sanitary stool seat appliance 65 consists of a single sheet of preferably medicated or sterilized paper, or other like foldable material, cut to the blank shape shown in Fig. 3, by reference to which it will be noticed the sheet is cut to include a main portion 1, provided with an opening 10, the surrounding edges 11 of which, inside and out, may be reinforced (as indicated by the dotted line α) in any suitable manner to maintain the said edges surrounding the 75 opening in a substantially rigid shape when the portion 1 is applied onto the stool seat, in the manner clearly shown in Figs. 1 and 2. It should be stated that while I have shown, (as in Fig. 1) the portion 1 formed 80 to the exact shape of the stool seat, the opposite outer edges thereof, 12—12, may be of sufficient width to cause them to fold down over the opposite side edges of the bowl when the user is seated thereon. 85

At the front end the sheet has an extended portion 2 which, as shown, is of sufficient width and length to constitute an apron 20 when the sheet is applied to the closet seat, it being understood that the said apron may 90 be of sufficient width to extend practically around and cover the entire front and opposite sides of the bowl.

The sheet portion 1 is also provided with a flap-like extension 3 at the front edge 95 extending within the opening 10, and the said portion 3, when the appliance is placed for use, as in Figs. 1 and 2, constitutes a protecting guard for the male when using 100 the closet.

4 designates another portion of the sheet that constitutes a supplemental cover, for fitting over the hinged seat cover 5 when the latter is swung against the wall or other solid bearing, and for sustaining the supplemental cover in position, it has an extension flap 40 adapted for being folded over the upper edge of the seat cover, to be clamped by such cover, against the wall, as is clearly shown in Fig. 2. 110

It will be noticed, particularly by referring to Fig. 1, at the points where the portions 1—4 and 1—2 connect, the sheet is restricted transversely, and thereby constitutes the lines on which the sheet may be conveniently and neatly folded upon itself into a compact and neat package, see Fig. 4. Furthermore, by reason of the restricted points of connection between the several distinct parts stated, the said parts will readily drop to the properly extended position, when it is desired to use the appliance, by simply taking hold of the flap 40. Furthermore, the flap constitutes a convenient means for hanging the entire device from the top of the seat cover and which is held to such position by reason of the cover clamping the flap against the wall, the peculiar connection of the body portion 1 with the supplemental cover and the connection of the front apron to the said body 1, operating to cause the parts 1, 2, 3 and 4 to quickly assume their proper position upon and in the stool seat.

It is obvious that the appliance can be so cheaply made that it can be liberally used and destroyed after using.

From the foregoing taken in connection with the drawing the complete construction or formation of my sanitary appliance, the manner of its use, and its advantages, will be readily apparent.

Among the advantages it should be mentioned arranging the several distinct portions in longitudinal alinement, as shown,

after the device has been hung onto the seat cover 5 by dropping the apron over the front edge of the bowl, the back, and the seat protecting portion and the member 3 will quickly assume their proper positions 40 without need of special adjustment by the user.

What I claim is:—

As a new article, a sanitary appliance for water closets comprising a single sheet of 45 foldable material, like medicated or sterilized paper, said sheet including an apertured main portion that constitutes a cover for the closet seat, a front extension that constitutes an apron for hanging over the bowl, a guard 50 extension into the aperture adapted to fold down within the bowl at the front, a back portion that constitutes a cover for the seat lid when raised, and a flap at the outer end of the lid cover portion adapted for being 55 clamped between the lid and the bearing against which the lid rests, the several separate portions, the apron, the seat cover, the lid cover, the flap and the guard being in longitudinal alinement, the sheet at the 60 junction of the lid cover, the apron portion and the seat portion and the flap connection with the lid cover constituting lines on which the sheet is foldable, whereby when folded with the flap outermost the sheet 65 opens out to drop in place over the lid, seat and bowl when the flap is secured between the lid and the bearing against which it rests when swung out.

JACOB P. YOUNG.
